UNITED STATES PATENT OFFICE.

EUGÈNE SCHNEIDER, OF PARIS, FRANCE, ASSIGNOR TO SCHNEIDER & CIE, OF PARIS, FRANCE, A LIMITED JOINT-STOCK COMPANY OF FRANCE.

GUN MOUNTED ON DOUBLE-TAILED CARRIAGE.

Application filed July 26, 1921. Serial No. 487,683.

To all whom it may concern:

Be it known that I, EUGÈNE SCHNEIDER, a citizen of the Republic of France, residing at 42, Rue d'Anjou, Paris, France, have invented new and useful Improvements in Guns Mounted on Double-Tailed Carriages, which is fully set forth in the following specification.

This invention has for its object to provide an improved construction of a gun mounted on a double-tailed gun carriage of the type described in my application filed June 9th, 1921, Serial No. 476,302.

The present invention further comprises an improvement in or relating to said gun.

The said improved construction and the said improvement are illustrated in the accompanying drawings in which:

Fig. 1 and 1^a comprise a sectional elevation taken in the longitudinal axial plane of the gun carriage.

Fig. 2 is a horizontal section on the line 2—2 of Fig. 1.

Fig. 3 is a cross-section on the line 3—3 of Fig. 1.

Fig. 4 is a partial section on the line 4—4 of Fig. 1.

Fig. 5 is a section on the line 5—5 of Fig. 3; and

Fig. 6 is a section on the line 6—6 of Fig. 1.

Like the gun described in my above-mentioned application the improved gun of the present invention comprises a wheeled axle, 35 that is an axle A and two wheels B. The carriage head C is fixed to the wheeled axle during firing.

The diyergible trails F which carry the anchoring devices at their rear ends, are 40 capable of assuming inclined positions relatively to the combination constituted by the wheeled axle B—A—B and the carriage head C.

In the illustrated example the possible inclination of the trails is obtained by mounting each of these trails on a ball and socket joint e projecting from the gun carriage head.

As shown in the drawings, the two ball 50 and socket joints may be formed on the ends of an axle c¹ which, as hereinafter described, serves as a pivotal axle for the saddle H on the carriage head as well as a rocking axle for the combined saddle and gun pedestal G

for producing the longitudinal uprighting of 55 the said gun pedestal.

The pivot pin g of the gun pedestal G (carrying the gun barrel) is formed by two trunnions that project respectively from the upper side and the lower side of the saddle 60 H. The longitudinal uprighting of the combined saddle H and gun pedestal G is produced by the movement of two toothed sectors h formed on the said saddle, meshing with pinions C¹ fixed on a cross shaft C² carried 65 by the carriage head C. This shaft carries externally a worm wheel sector C³ that is actuated by means of a worm C⁴ journaled in the carriage head C. The worm C⁴ is driven by means of gearing C⁵—C⁶—C⁷—C⁸. 70

The carriage head C, together with the saddle H and the gun pedestal G may be up-righted transversely by oscillation around an axle J carried in a bracket A¹ fixed to the axle A. This oscillatory motion is produced 75 by the rolling of a worm C⁹ over a worm wheel sector A² carried by the bracket A¹. This worm C⁹ is fixed on a shaft C¹⁰ journaled in the carriage head C. This shaft C¹⁰ is driven by means of gearing C¹¹— 80 C¹²—C¹³—C¹⁴.

The training movement of the gun pedestal G is produced by the rolling movement of a worm G¹ over a worm wheel sector H¹ carried by the saddle H. 85

This worm G¹ is fixed on a shaft G² journaled in the gun pedestal G; it receives its motion through gearing G³—G⁴—G⁵—G⁶—G⁷—G⁸.

The elevation of the cradle S carrying the gun barrel is produced by the movement of the toothed sector R around a pinion G⁹ fixed on a shaft G¹⁰ carrying a worm wheel G¹¹ which is actuated by a worm G¹² that receives its motion through gearing G¹³— 95 G¹⁴—G¹⁵. The kinematic connection between the trails F is effected in the known manner by means of a cross rocking beam F¹ fulcrumed at its centre by means of a ball and socket joint f¹ on a cylindrical pivot 100 pin C¹⁵ formed on the carriage head C.

The cross beam F¹ carries at its ends ball and socket joints F² to which are articulated the lower ends of two arms F³ whose upper ends F⁴ are fixed to the trails F and are fitted 105 upon the ball and socket joints e.

One of the essential characteristic features of the improved construction which

constitutes an improvement applicable to all the constructional forms described in my above-mentioned application, consists in the peculiar arrangement of a device for balancing the rocking mass, and in the manner of its connection to the carriage head, said connection being made in such a manner as to facilitate the longitudinal uprighting of the combined saddle H and gun pedestal by 10 rocking around the axle c¹.

The device for balancing the rocking mass around the cradle trunnions s, in the elevating of the gun, comprises two cylinders K pivoted to the said cradle by means of trunnions k and in each of which a piston K¹ is adapted to move.

A spring L is coiled around the rod K² of this piston. This spring bears at one end against the piston, and at its other end 20 against one of the ends of the cylinder K.

When the cradle and the gun barrel are in their horizontal position, the spring L is pressed and kept stressed by the fact that the free end k² of the piston rod K² is attached 25 to the carriage head by means of a cable or metal band M fastened at one end m at k² whilst its other end m¹ is attached to a cross beam N which is fulcrumed at its centre by means of a stud n in the carriage head C.

10 The cable or band M is guided by a pulley O movable around an axle pin o carried by the gun pedestal G. In order that the pull upon the rod K² shall act always along the axis of this rod, the cable or band M before 15 passing over the guiding pulley O passes under a boss G¹⁶ projecting from the gun pedestal G.

When the parts are in the positions indicated in the figure, that is to say, when the 0 cradle is horizontal the effort that tends to cause the oscillating mass to turn downwards by rocking on the trunnions s, is balanced approximately by the tension of the spring L which has a tendency to cause the mass 5 to rock in the opposite direction with a leverage equal to the distance between the piston rod and the axis of the gun cradle trunnions. The result is that the displacement of the 10 elevating sector R over the pinion G⁹, can 0 be effected without the necessity of exerting any considerable force.

At the same time, the illustrated apparatus 5 allows of balancing the mass that rocks around the axis c¹ for the uprighting movements of the combined gun pedestal G and the saddle H, which allows of producing without any appreciable exertion of force, a displacement of the sectors h over the pinions C¹. As a matter of fact the pivotal 10 movement of the combined gun barrel, gun cradle, gun pedestal G and saddle H around the axle c¹, has a constant tendency to take place with an effort represented by the product of the weight of the oscillating mass 5 multiplied by a leverage equal to the dis-

tance between the vertical line passing through the centre of gravity of the said mass and the axis c¹.

In the uprighting movements, this effort is approximately balanced by the action of the balancer. It is for this purpose that the piston rod K² is coupled to a band which, instead of being attached directly to the carriage head, passes over a guide pulley carried by the gun pedestal. Moreover, the coupling of the piston rod, as above stated, is effected by means of bands attached to the ends of the cross bar N pivoted on the gun carriage head; this allows of a suitable action of the balancer irrespective of the training positions.

I claim:

1. A double-trailed wheeled gun mounting comprising a gun carriage head, a saddle pivotally mounted in said carriage head, a pedestal pivotally mounted on said saddle, a pivotal axle supporting said saddle in said carriage head, said axle constituting the axis around which the saddle and pedestal oscillates, the ends of said axle projecting externally from the carriage head to form two spherical joint elements for the articulation of the trails thereto.

2. In a device of the class described, the combination of a gun carriage head, a saddle pivotally mounted in said carriage head, a pedestal pivotally mounted in said saddle, a balancer adapted to facilitate the longitudinal uprighting of said saddle and pedestal, said balancer comprising one or more cylinders articulated to a gun cradle, a piston and piston rod in said cylinder, means for resisting movement of said piston, and a member connected at one end to said piston rod and at its opposite end to a crossbeam pivoted in said carriage head.

3. In a device of the class described, the combination of a gun carriage head, a gun saddle, an axle supporting said saddle in said carriage head, a gun pedestal supported by said saddle, and a balancer adapted to facilitate the longitudinal uprighting of said saddle and pedestal.

4. In a device of the class described, the combination of a carriage head, a gun saddle, an axle supporting said saddle in said carriage head, a gun pedestal supported by said saddle, a pair of trails having ball and socket connection with said axle, and a balancer adapted to facilitate the longitudinal uprighting of said saddle and pedestal.

5. In a device of the class described, the combination of a carriage head, a gun saddle, an axle supporting said saddle in said carriage head, a pedestal supported by said saddle, a gun cradle carried by said pedestal, and a balancer secured to said cradle and carriage.

6. In a device of the class described, the combination of a gun carriage head, a gun

saddle, an axle supporting said saddle in said carriage head, a gun pedestal supported by said saddle, a gun cradle carried by said pedestal, elevating mechanism for said 5 cradle, and means whereby the actuation of said elevating mechanism is facilitated.

7. In a device of the class described, the combination of a carriage head, a gun saddle, an axle supporting said saddle in said 10 carriage head, a gun pedestal supported by said saddle, training mechanism for said pedestal, and a balancer for the saddle and pedestal, said balancer being adapted to operate in all the training positions of the 15 pedestal.

8. In a wheeled-axle gun mount, a carriage head mounted on the axle, means for moving said head about an axis at right

angles to said axle, gun supporting means mounted in said carriage head, and a bal- 20ancer whereby the longitudinal uprighting of said gun supporting means is facilitated.

9. In a device of the class described, a gun carriage head, an axle carried by said carriage head, and gun supporting means 25 carried by said axle, the ends of the axle projecting externally from the carriage head to form spherical joint elements for the articulation of trails thereto.

In testimony whereof I have signed this 30 specification.

EUGÈNE SCHNEIDER.
